UNITED STATES PATENT OFFICE.

RICHARD WATKINS AND JOHN DICKSON, OF NEW YORK, N. Y.

WATER-TUBE BOILER.

SPECIFICATION forming part of Letters Patent No. 412,438, dated October 8, 1889.

Application filed July 6, 1889. Serial No. 316,715. (No model.)

To all whom it may concern:

Be it known that we, RICHARD WATKINS and JOHN DICKSON, citizens of the United States, residing at New York city, in the county of New York and State of New York, have invented certain new and useful Improvements in Water-Tube Boilers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates generally to stationary land and marine boilers, but particularly to water-tube boilers.

We will first describe the invention in connection with the drawings, and then point it out in the claim.

Figure 1 of the drawings is an elevation in longitudinal section; Fig. 2, a vertical cross-section, and Fig. 3 a detail view showing the corrugation of the boiler metal.

In the drawings, A represents the boiler as an entirety; B, the return fire-tubes; C C, the horizontal fire-flues; c, the water-tubes running from the front head a to the back head a', through said flues, the heads a a' being tapped to receive the brass plugs D, which are opposite the tube-end holes where they open into the water-space.

E represents the furnace-chamber, divided by a water-leg or partition E', and provided with the usual grate-bars e, fire-doors e', and bridge-wall F in each division. In addition to the usual bridge-wall F, we make another wall F', extending down from the upper part of each flue C, just where the water-tubes c enter the chamber G, in which the products of combustion rise to enter the return-tubes B, and thence pass out through the uptake H. The function of the wall F is to deflect the products of combustion downwardly, and thus cause them to dwell longer among the water-tubes and part with more of their heat.

The water-space I surrounds the fire-place

of the boiler and extends into the legs h h and partition-leg E'.

J K L are man-holes to allow access to the interior of the boiler for the purpose of cleaning it out, and M a steam-drum connecting with the steam-space of the boiler by means of the necks m.

We are well acquainted with the boiler described in Patent No. 348,315, granted to Burrows, August 31, 1886; but it has only one large furnace and that one in the large flue. Hence the water-tubes are crowded down into the fuel, while the fire comes into such close contact with the water-tubes that the water is liable to be driven out and the tubes to be burned. There is also found to be insufficient room in this boiler for fire thickness and for grate-surface. In order to remove these objections, we have made two independent furnaces, each with its own fire-door, so that one may be cleaned out while the other is in full operation, thus preventing the admission of cold air to the heating-surface of all the tubes. Our construction also avoids the crowding of the water-tubes down into the fire, so that the water in our tubes is not liable to be driven out and the tubes to be burned. In order to render unnecessary the usual bracing against collapsing pressure, we corrugate the flues C, as shown in Fig. 3 of the drawings, thereby also increasing the heating-surface.

What we claim as new, and desire to protect by Letters Patent, is—

A steam-boiler having the lower part divided by a water-leg partition into two compartments, and having in each of these compartments a separate furnace, a separate fire-flue, and the water-tube c, the latter running through said flues from head a to head a', as and for the purpose set forth.

In testimony whereof we affix our signatures in presence of two witnesses.

RICHARD WATKINS.
JOHN DICKSON.
